US0D1069560S

(12) **United States Design Patent** (10) Patent No.: **US D1,069,560 S**
(45) Date of Patent: ** Apr. 8, 2025

(54) **CABLE HANGER**

(71) Applicant: **Cambria County Association for the Blind & Handicapped**, Johnstown, PA (US)

(72) Inventors: **Timothy Joseph Wedding**, Johnstown, PA (US); **John William Giffin**, Johnstown, PA (US)

(73) Assignee: **CAMBRIA COUNTY ASSOCIATION FOR THE BLIND AND HANDICAPPED**, Johnstown, PA (US)

(**) Term: **15 Years**

(21) Appl. No.: **29/902,473**

(22) Filed: **Sep. 13, 2023**

(51) LOC (15) Cl. **08-11**

(52) U.S. Cl.

USPC **D8/367**

(58) **Field of Classification Search**

USPC D8/367, 354, 349, 356, 395; D12/162; D13/153

CPC A47G 29/083; F16B 45/00; B60P 7/0823; H02G 3/32; F16L 3/14; B44D 3/14

(57) **CLAIM**

The ornamental design for a cable hanger as shown and described.

DESCRIPTION

FIG. 1 is a first isometric view of the cable hanger; FIG. 2 is a second isometric view of the cable hanger; FIG. 3 is a front view of the cable hanger; FIG. 4 is a rear view of the cable hanger; FIG. 5 is a top view of the cable hanger; FIG. 6 is a bottom view of the cable hanger; FIG. 7 is a left view of the cable hanger; and, FIG. 8 is a right view of the cable hanger. The broken lines in the drawings depict environmental subject matter only and form no part of the claimed design.

1 Claim, 6 Drawing Sheets
